UNITED STATES PATENT OFFICE.

WILLIAM C. CARTER, OF ST. LOUIS, MISSOURI.

FUEL-SUPPLY APPARATUS.

1,146,134.

Specification of Letters Patent. Patented July 13, 1915.

Application filed July 6, 1914. Serial No. 849,353.

To all whom it may concern:

Be it known that I, WILLIAM C. CARTER, a citizen of the United States, residing at St. Louis, Missouri, have invented a certain new and useful Improvement in Fuel-Supply Apparatus, of which the following is a full, clear, and exact description, such as will enable others skilled in the art to which it appertains to make and use the same.

10 This invention relates to fuel supply devices for internal combustion engines, and particularly to devices of the type illustrated and described in my pending application for patent, Serial #825,130, filed March 16, 15 1914.

The main object of my present invention is to provide a fuel supply device of the general type mentioned which is so designed that the fuel from the source of supply can- 20 not flow into the gravity feed reservoir, and flood same when the tank containing the supply of fuel is in a higher horizontal plane than said reservoir or the valved passageway that is arranged between said tank 25 and reservoir.

Another object is to provide a fuel supply apparatus of the type referred to which comprises means for holding the inlet valve of the valved passageway seated in case the 30 automobile on which the apparatus is installed is traveling down an incline or is arranged in such a position that the fuel in the pipe leading from the supply tank exerts pressure on said valve.

35 Another object is to provide a fuel supply device of the general type mentioned which comprises means for preventing carbon from the engine from entering the pump that draws the fuel from the source of supply and forces it into the reservoir which feeds the carburetor of the engine. And still another object is to provide a novel kind of valve mechanism for a fuel supply apparatus of the kind described in my pending application previously referred to.

45 Other objects and desirable features of my invention will be hereinafter pointed out.

Figure 1 of the drawings is a side elevational view illustrating my improved fuel supply device applied to an internal combustion engine. Fig. 2 is an enlarged vertical sectional view of the reservoir, from

which the fuel is supplied by gravity to the engine. Fig. 3 is a vertical sectional view taken on the line 3—3 of Fig. 2. Fig. 4 is a vertical sectional view taken on the line 4—4 of Fig. 2. Figs. 5 and 6 are horizontal sectional views taken on the lines 5—5 and 6—6, respectively, of Fig. 2. Fig. 7 is a perspective view of the member at the lower end of the reservoir which sustains the vertically disposed tube that projects upwardly through the reservoir, and which also acts as a guide for the inlet valve. Fig. 8 is a perspective view of the member in said tube that forms part of the valved passageway and also guides the shiftable member that carries the outlet valve; and Fig. 9 is a perspective view of the outlet valve or discharge valve and the member that carries same.

Referring to the drawings which illustrate one form of my invention, A designates a fuel supply tank that holds a quantity of liquid fuel which is supplied to the carburetor B of an internal combustion engine C when the engine is in operation, and D designates a reservoir arranged intermediate said supply tank and carburetor in such a position that the fuel will flow from same to the float chamber of the carburetor by gravity. A pump E of any preferred type or design is provided for drawing the fuel from the supply tank A and forcing it into the reservoir D, and means are provided for causing the supply of fuel to said reservoir D to cease automatically whenever the fuel in said reservoir exceeds a certain quantity.

The apparatus herein shown is similar to the apparatus illustrated in my pending application previously referred to, in that it comprises a valved passageway F arranged intermediate the supply tank A and reservoir D and provided with an inlet and an outlet check valve that open automatically when the pump is in operation, so as to cause fuel to enter said passageway and be forced from same into the reservoir intermittently so long as the fuel in said reservoir remains below a certain level, but the check valves and also the means for automatically cutting off the supply of fuel to the valved passageway F are of slightly different construction from the corresponding parts of the apparatus described in my

pending application. The apparatus herein shown also differs from the apparatus described in my previously mentioned pending application, in that it comprises a means 5 separate and distinct from the weight of the fuel in the valved passageway F for holding the inlet valve seated in case the supply tank A becomes arranged in a higher horizontal plane than said inlet valve.

10 The pump E that I prefer to use is of the diaphragm type and consists of a casing formed by two disk-shaped members 1 whose peripheral edge portions clamp the peripheral edge portion of a diaphragm 2, 15 to which they are clamped tightly by rivets or bolts 3 that pass transversely through said parts. The diaphragm 2 of the pump may either be plain or corrugated and formed from any suitable material. In 20 practice I prefer to form the diaphragm 2 from vanadium steel and arrange a coiled compression spring 4 on one side of same, the side next to the valved passageway, as shown in Fig. 2, so as to move the diaphragm 25 in one direction. The other side of the casing of the pump in which the diaphragm is arranged is connected by means of a pipe 5 with one cylinder of the engine or with the exhaust pipe of the engine, so 30 that pressure will be exerted on the diaphragm to move it in the opposite direction. A screening device is combined with said pipe 5 so as to prevent the carbon from the engine from entering the casing of the pump 35 E, and in the form of my invention shown in Fig. 2 said screening device consists of a cylindrical-shaped screen 6 that is arranged in a tubular-shaped member 7 on one side of the pump casing into which the 40 pipe 5 leads. The lower end of said member 7 is closed by a cap nut 8 which is provided with a chamber 8^a for receiving the carbon that enters through the pipe 5, and which is collected by the screen 6, and said 45 tubular-shaped member 7 is provided at one side with a boss 7^a that is screwed into one of the disks that form part of the casing of the pump E. The spring 4 on the opposite side of the diaphragm of the pump is 50 arranged in a chamber formed in a nipple 9 that is screwed into one side of the pump casing and also tapped into a boss 10 on the lower end of the reservoir D which has an opening 10^a that leads to the valved passageway F of the apparatus, thus establishing 55 direct communication between the pump and the passageway F. When the engine is in operation the pump E draws a charge of fuel into the passageway F when the diaphragm 2 of the pump moves in one direction and forces said charge out of the passageway and into the reservoir D when the diaphragm 2 of the pump moves in the opposite direction.

In the apparatus herein shown an inlet 65 check valve 11 is provided for controlling the flow of fuel into the valved passageway F, and an outlet check valve 12 is provided for controlling the flow of the fuel from the passageway F into the reservoir D. The inlet valve 11 preferably consists of a horizontally disposed disk, as shown in Fig. 2, that is seated on the upper side of a nipple 13 that connects the fuel supply pipe 13^a to the boss 10 on the lower end of the reservoir 70 D. The outlet valve or discharge valve 12 preferably consists of a flap valve or swinging valve that normally closes an outlet port or discharge port 12^a formed in the side wall of the passageway F adjacent the upper end 75 of same, as shown in Fig. 2, said outlet valve 12 opening outwardly or away from the passageway F so as to permit the fuel to escape from said passageway into the reservoir D, or rather into a vertically disposed tube 14 80 that projects upwardly through said reservoir. This tube 14 is supported by a member 15 that is screwed into the bottom of the reservoir D, and which is provided at its lower end with a guide 16 that receives a 85 stem 11^a on the top side of the inlet valve 11, thus guiding said inlet valve properly and preventing it from canting. The outlet valve 12 is preferably carried by a shiftable member 17 whose position is governed by 90 the float in the reservoir D, said member and float being connected together in such a manner that after a certain quantity of fuel has entered the reservoir D the member 17 will shift automatically into such a position that the valve 12 on said member will not cover the discharge port 12^a through 95 which the fuel escapes from the passageway F. A member G that is arranged in the lower end of the tube 14 forms the top wall 100 and also a portion of one of the side walls of the valved passageway F, and, in addition to this function, acts as a guiding and retaining device for the shiftable member 17 which carries the discharge valve 12. 105

The member G may be described as consisting of a hollow member provided at its lower end with a cylindrical-shaped part 18 that fits snugly inside of the tube 14 and having a reduced upper portion of about one-half the diameter of the lower portion 18, the discharge port 12^a being formed in the vertical wall of said upper reduced portion, as shown in Fig. 8, and the valve 12 being arranged on the outside 115 of said wall, as shown in Fig. 2. At the upper end of the member G is a pair of vertically disposed guides 19 that embrace the valve-carrying member 17, and thus holds said member in an upright position 120 in the tube 14, the lower edge of the valve-carrying member 17 normally resting on a stop 20 between the guides 19. The outlet 125

valve 12 is hinged or pivotally connected to the member 17 in such a manner that it can swing outwardly away from the vertical wall of the passageway F in which the 5 discharge port 12^a is formed, the valve 12 herein shown being provided with a hook 12^b that projects through an opening 12^c in the valve-carrying member 17, as shown clearly in Fig. 4. A depending portion 10 17^a on the valve-carrying member 17 that lies between the valve 12 and the inner side of the tube 14 acts as a stop to limit the opening movement of the valve 12, said depending portion 17^a and the valve 12 being 15 so proportioned that the lower edges of same will be normally spaced away from the top of the cylindrical-shaped portion 18 of the member G, above which they lie, so that small particles of dirt or foreign matter 20 which lodge on the top of the cylindrical-shaped portion of the member G will not interfere with the movement of the valve 12. The member 17 normally occupies the position shown in Fig. 2 so that the valve 25 12 will lap over the port 12^a, but means are provided for automatically shifting the member 17 into such a position that the valve 12 will not close the port 12^a when the fuel in the reservoir D rises above a certain 30 level. In the form of my invention herein shown said means consists of a rod 21 that connects the valve-carrying member 17 with the float 22 that is arranged inside of the reservoir D, said rod being arranged 35 inside of the tube 14 and provided with a spider or guiding device 23 that cooperates with the tube 14 to center said rod, and thus accurately guide the valve-carrying member 17.

40 In order to eliminate the possibility of the fuel from the supply tank A flowing into the reservoir D and flooding same, in case the supply tank A becomes arranged in such a position that gravity will cause 45 the fuel to flow from same toward the valved passageway F and exert pressure on the inlet valve 11, as, for example, in case the automobile on which the apparatus is installed is on an incline, I have provided 50 means separate and distinct from the weight of the fuel in the passageway F for holding the inlet valve 11 seated. Said means preferably consists of a spring 24 that exerts sufficient downward pressure on the 55 valve 11 to hold it seated, even when the supply tank A is arranged in a higher horizontal plane than the reservoir D, or the passageway F, said spring 24 being weaker than the spring 4 of the pump E so that the 60 valve 11 will be unseated by the suction exerted on same when the pump is in operation. While I prefer to employ a spring for holding the inlet valve seated, I wish it to be understood that my invention is not limited to the use of a spring of the 65 particular construction herein shown, or, in fact, to any particular kind of means for preventing the inlet valve opening accidentally, for my broad idea consists in a fuel supply apparatus of the type described, 70 in which the means that governs the admission of fuel to the valved passageway between the supply tank and the reservoir D is so designed that the pressure which the fuel exerts on the inlet valve when the 75 automobile is traveling down an incline will not be sufficient to force the inlet valve open and thus flood the reservoir D. The spring 24 herein shown is a coiled expansion spring that is seated in the pocket in 80 the lower end of the member G and whose lower end projects into the stem 11^a of the inlet valve that projects upwardly through the guide 16 on the member 15.

The reservoir D is provided with a removable cover 25 that is retained in position by means of a flat leaf spring 26 on the underside of same whose end portions project under inwardly projecting stops 27 on the side walls of the reservoir D. Said 85 spring 26 is connected to a boss 28 on the underside of the cover 25, which is provided with a vent opening 29 that has lateral inlets 29^a, as shown in Fig. 2, the intermediate portion of said spring being wide 90 enough so that it will prevent the fuel from splashing upwardly into the vent opening 29.

When the engine is in operation charges 95 of fuel will be drawn into the valved passageway F and forced into the reservoir D intermittently, so long as the fuel in the reservoir D remains below a certain level, the movement of the diaphragm 2 of the pump E in one direction opening the inlet 100 valve 11 and causing a charge of fuel to be drawn into the passageway F, and the movement of said diaphragm in the opposite direction causing said charge to be forced out of said passageway through the discharge 105 port 12^a into the tube 14 whose upper end opens in the reservoir D. So long as the fuel in the reservoir D remains below a certain level a charge of fuel will be forced 110 into the reservoir at each cycle of operations 115 of the pump E, but as soon as the float 22 in said reservoir rises high enough to shift the valve-carrying member 17 into such a position that the discharge valve 12 does not cover the port 12^a, the supply of fuel to 120 the passageway F will cease automatically, owing to the fact that said passageway F will then be in communication with the reservoir, and consequently, the suction and pressure which the pump creates in the passageway F will merely cause the fuel to surge back and forth between said reservoir 125 and passageway through the port 12^a. When

the level of the fuel in the reservoir D drops the valve-carrying member 17 will move automatically back to its normal position, and thus cause the valve 12 to lap over the discharge port 12^a so that on the succeeding stroke of the pump sufficient suction will be created in the passageway F to unseat the inlet valve 11 and draw a charge of fuel into said passageway from the supply tank.

10 While I prefer to cut off the flow of fuel to the passageway F by holding the discharge valve 12 open so long as a certain quantity of fuel remains in the reservoir D, I do not wish it to be understood that my 15 invention is limited to an apparatus of this type in which the supply of fuel to said passageway is governed in this manner, for the supply of fuel to the passageway F could be interrupted in various other ways 20 without departing from the spirit of my invention.

In an apparatus of the character described there is no possibility of the reservoir D being flooded in case the supply tank 25 A becomes arranged in a higher horizontal plane than the reservoir, or, in other words, arranged in such a position that the fuel will flow by gravity to the valved passageway F and exert pressure on the inlet valve, 30 owing to the fact that means are provided for counteracting any tendency of the inlet valve 11 to open when the fuel in the pipe leading from the supply tank exerts pressure on said valve. Another desirable feature of such an apparatus is that it comprises 35 means for preventing carbon from the engine from entering the pump E, which means is so designed that it can be cleaned easily to remove the carbon that collects 40 therein. And still another desirable feature of such an apparatus is the simplicity and certainty of operation of the inlet and outlet check valves of the valved passageway through which the fuel has to pass before 45 entering the reservoir D.

Having thus described my invention, what I claim is:

1. A fuel supply device for internal combustion engines, comprising a reservoir from 50 which fuel is fed to the engine by gravity, a passageway arranged intermediate said reservoir and a supply of liquid fuel, means for drawing fuel from the source of supply into said passageway and thereafter forcing 55 said fuel into said reservoir, and an inlet valve mechanism in said passageway constructed in such a manner that it will not open accidentally in case fuel from the source of supply exerts pressure on same.

60 2. A fuel supply device for internal combustion engines, comprising a reservoir from which fuel is fed to the engine by gravity, a passageway arranged intermediate said reservoir and a supply of liquid fuel, means

for drawing fuel from the source of supply 65 into said passageway and thereafter forcing said fuel into said reservoir, an inlet valve for said passageway, and means for holding said valve seated in case the supply of fuel becomes arranged in a higher horizontal 70 plane than said valve.

3. A fuel supply device for internal combustion engines, comprising a reservoir from which fuel is fed to the engine by gravity, a passageway arranged intermediate said reservoir and a supply of liquid fuel, means for drawing fuel from the source of supply 75 into said passageway and thereafter forcing said fuel into said reservoir, an inlet valve for said passageway, and a spring which exerts pressure on said valve and prevents it from opening accidentally.

4. A fuel supply device for internal combustion engines, comprising a reservoir from which fuel is supplied to the engine 85 by gravity, a passageway arranged intermediate said reservoir and a supply of liquid fuel, means for drawing charges of fuel into said passageway and forcing said charges into said reservoir intermittently, 90 means for causing the supply of fuel to said reservoir to cease automatically when the fuel in the reservoir exceeds a certain quantity, an inlet valve for said passageway, and means for preventing said inlet valve from 95 opening accidentally in case the supply of fuel becomes arranged in such a position that said inlet valve is subjected to the pressure of the weight of the fuel in the supply line leading to the passageway.

5. A fuel supply device for internal combustion engines, comprising a reservoir from which fuel is supplied to the engine by gravity, a passageway arranged intermediate 105 said reservoir and a supply of liquid fuel, an inlet check valve for said passageway, a swinging outlet check valve for said passageway, and means for drawing charges of fuel into said passageway and forcing said charges into said reservoir.

6. A fuel supply device for internal combustion engines, comprising a reservoir from which fuel is supplied to the engine by gravity, a passageway arranged intermediate 115 said reservoir and a supply of liquid fuel, an inlet check valve for said passageway, a swinging outlet check valve for said passageway, means for drawing charges of fuel into said passageway and forcing said charges into said reservoir, a member which 120 carries said outlet valve, and means for shifting said valve-carrying member into such a position after a certain quantity of fuel has entered said reservoir that said outlet valve will be inoperative.

7. In a fuel supply device of the character described, a reservoir from which fuel is supplied to the engine by gravity, a pas-

- 5 sageway arranged intermediate said reservoir and a supply of liquid fuel and having a vertical wall that is provided with a port, an inlet check valve for said passageway, a 5 pivotally mounted outlet valve arranged on the outside of said passageway for controlling the port in the vertical wall of said passageway, and a pump communicating with said passageway intermediate said valves.
- 10 8. In a fuel supply device of the character described, a reservoir from which fuel is supplied to the engine by gravity, a passageway arranged intermediate said reservoir and a supply of liquid fuel and having a vertical wall that is provided with a port, an inlet check valve for said passageway, a 15 pivotally mounted outlet valve arranged on the outside of said passageway for controlling the port in the vertical wall of said passageway, a pump communicating with said passageway intermediate said valves, and means for automatically shifting said outlet valve into an inoperative position when the fuel in said reservoir rises above a 20 certain level.
- 25 9. In a fuel supply device for internal combustion engines, a reservoir from which fuel is supplied to the engine by gravity, a passageway arranged intermediate said reservoir and a supply of liquid fuel provided with an inlet valve and with a swinging outlet valve, a vertically disposed tube projecting upwardly from the bottom of said reservoir, and a shiftable member in said tube carrying said outlet valve and whose position is governed by the level of the fuel in 30 said reservoir.
- 35 10. In a fuel supply device for internal combustion engines, a reservoir from which fuel is supplied to the engine by gravity, a passageway arranged intermediate said reservoir and a supply of liquid fuel provided with an inlet valve and with a swinging outlet valve, a vertically disposed tube projecting upwardly from the bottom of 40 said reservoir, a shiftable member in said tube carrying said outlet valve and whose position is governed by the level of the fuel in said reservoir, means in said tube for guiding said valve-carrying member vertically, and means on said valve-carrying member for limiting the movement of said outlet valve.
- 45 11. In a fuel supply device for internal combustion engines, a reservoir from which fuel is supplied to the engine by gravity, a hollow member projecting upwardly into said reservoir and provided with a vertical wall in which a port is formed, a flap valve 50 arranged on the outside of said wall for closing said port, and a shiftable member that carries said valve.
- 55 12. In a fuel supply device for internal combustion engines, a reservoir from which fuel is supplied to the engine by gravity, a passageway arranged intermediate said reservoir and a supply of liquid fuel and provided with an inlet valve, a pivotally mounted outlet valve for said passageway, a 55 spring that exerts pressure on said inlet valve, a diaphragm pump having one side of its casing connected with said passage- 60
- 65 fuel is supplied to the engine by gravity, a hollow member projecting upwardly into said reservoir and provided with a vertical wall in which a port is formed, a flap valve arranged on the outside of said wall for closing said port, a shiftable member that carries said valve, vertically disposed guides in which said valve-carrying member is guided vertically, and a float in said reservoir connected to said valve-carrying member.
- 70 75 13. In a fuel supply device for internal combustion engines, a reservoir from which fuel is supplied to the engine by gravity, a passageway arranged intermediate said reservoir and a supply of liquid fuel, an outlet valve for said passageway, a horizontally disposed disk-shaped inlet valve for said passageway, a stem on said inlet valve, a stationary guide through which said stem passes, and a pump communicating with said passageway intermediate said valves.
- 75 80 14. In a fuel supply device for internal combustion engines, a reservoir, a vertically disposed tube projecting upwardly through said reservoir, a hollow member in said tube forming part of a valved passageway and having a vertical wall in which an outlet port is formed, a shiftable valve-carrying member in said tube provided with a flap valve that co-operates with said port, and vertically disposed guides on said member that embrace said valve-carrying member.
- 85 15. A fuel supply device for internal combustion engines, comprising a reservoir for supplying fuel to the engine by gravity, means for drawing charges of fuel from a source of supply and forcing said charges into said reservoir intermittently, a removable cover for said reservoir having a vent opening formed therein, and a retaining device for said cover which is so arranged that the fuel in said reservoir cannot splash out of the vent opening in said cover.
- 90 100 16. In a fuel supply device of the character described, a reservoir, a removable cover for said reservoir, a boss on the underside of said cover provided with a vertically disposed vent opening that has lateral inlets, and a retaining device for said cover connected to said boss in such a manner that it prevents the fuel from splashing out of said vent opening.
- 95 105 110 17. A fuel supply device for internal combustion engines, comprising a reservoir for supplying fuel to the engine by gravity, a passageway arranged intermediate said reservoir and a supply of liquid fuel and provided with an inlet valve, a pivotally mounted outlet valve for said passageway, a 115 spring that exerts pressure on said inlet valve, a diaphragm pump having one side of its casing connected with said passage-

way intermediate said valves and the other side of said casing connected with a cylinder or with the exhaust pipe of the engine, and means in said reservoir for automatically shifting said outlet valve into an inoperative position whenever the fuel in said reservoir rises above a certain level.

In testimony whereof I hereunto affix my signature in the presence of two witnesses, this thirtieth day of June 1914.

WILLIAM C. CARTER.
